HYDROTHERAPY BATH UNIT

Samuel L. McNair, Overland Park, Kans., assignor to
The Songrand Corporation

Filed Apr. 20, 1971, Ser. No. 134,112

Term of patent 14 years

Int. Cl. D24—01

U.S. Cl. D83—1

Fig. 1.

Fig. 2.

Fig. 3.

FIG. 1 is a top plan view of a hydrotherapy bath unit showing my new design;

FIG. 2 is a bottom plan view of same;

FIG. 3 is a side elevational view of same;

FIG. 4 is another side elevational view of same;

FIG. 5 is an end elevational view of same taken generally from the right-hand end as viewed in FIG. 4;

FIG. 6 is an end view of same taken from the left-hand end as viewed in FIG. 4; and

FIG. 7 is a fragmentary sectional view taken generally along line 7-7 of FIG. 1 in the direction of the arrows.

I claim:

The ornamental design for a hydrotherapy bath unit, as shown and described.
